UNITED STATES PATENT OFFICE.

FRANK KINZBACH, OF HOUSTON, TEXAS.

MACHINE FOR CLEANING AND RECONDITIONING PIPE.

Application filed December 6, 1924. Serial No. 754,449.

This invention relates to new and useful improvements in a machine for cleaning and re-conditioning pipe.

One object of the invention is to provide a machine of the character described specially designed for cleaning and painting pipe, and pipe-lines, particularly pipe lines that have been buried beneath the ground, which, at intervals must be cleaned and re-painted.

Another object of the invention is to provide a machine of the character described which is designed to be supported by the pipe being cleaned, said pipe forming a track on which the machine runs while in operation, and the machine is so designed that it may be readily mounted on the pipe and dismounted therefrom.

A further feature of the invention resides in the provision of novel means whereby the pipe may be thoroughly coated with a uniform coat of paint, simultaneously with the cleansing operation.

With the above and other objects in view this invention has particular relation to certain novel features of construction, operation and arrangement of parts, an example of which is given in this specification and illustrated in the accompanying drawings,

wherein:—

Figure 1 shows a side elevation of the machine.

Figure 2 shows a plan view thereof.

Figure 3 shows a fragmentary rear elevation thereof, mounted on the pipe which is shown in section, taken on the line 3—3 of Figure 2.

Figure 4 shows a transverse sectional view taken on the line 4—4 of Figure 1.

Figure 5 shows a fragmentary sectional view taken on the line 5—5 of Figure 4.

Figure 6 shows a transverse sectional view taken on the line 6—6 of Figure 1, and

Figure 7 shows a transverse sectional view taken on the line 7—7 of Figure 1.

Referring now more particularly to the drawings, wherein like numerals of reference designate similar parts in each of the figures, the numeral 1 designates the pipe being cleaned and reconditioned. At intervals buried pipe lines must be raised and cleaned and repainted. The machine is illustrated as accomplishing this work.

The frame of the machine includes suitable side members 2, 2. These side members are preferably channel irons, and they are

connected by suitable arches, as 3. A motor 4 is mounted on the rear end of the frame and associated with it is the fuel tank 5. The machine is mounted on the front and rear carrier wheels 6, 6 and 7, 7. These carrier wheels are fixed on the respective axles 8 and 9 which run in suitable end bearings depending from the frame. These respective carrier wheels are spaced apart and run on the pipe 1. The front wheels 6 are serrated, having ratchet-like teeth which engage with the pipe to propel the machine along, and the inner corners of the rear wheels 7 bite into the pipe to hold the machine in vertical position thereon.

The motor shaft 10 has a spur gear 11, fixed thereon, which is in mesh with and drives the spur gear 12, fixed on the line shaft 13, and this line shaft carries a fixed screw gear 14 which is in mesh with and drives a worm gear 15, fixed on the front axle 8. The machine is thus propelled along the pipe 1.

Swung from the front end of the frame there is the bearing ring 16 which is fastened to the respective side members 2 by means of the arms 17, 17. This ring is formed with spaced bearings 18 through which the bearing rods 19 extend, and on the respective ends, of these rods, which extend beyond said bearings, the respective rollers 20, are mounted, and these rollers may be provided with any desirable type of anti-friction bearings. Within the ring 16 there is a sleeve 21 formed with the rear and front peripheral annular flanges 22 and 23 which abut against the adjacent rollers 20 and confine said rollers in the raceways thus provided. Both the bearing ring 16 and the sleeve 21 are formed of two lengthwise sections, as shown in Figure 1. The abutting parts of the ring sections are formed with adjacent outturned ears 24, 25 to the former of which the lock bolts 26 are pivoted, which are adapted to fit through the slots 27, of the latter, and are locked therein by means of lock nuts 28 threaded onto said bolts, and which may be unscrewed to release said bolts to take the ring sections apart. The sections of the sleeve 21 have abutting ears 29 with set bolts 30 securing them, and the sleeve sections, together.

The flange 22, of the sleeve 21, is formed with a gear face 31, which is in mesh with, and driven by the intermediate spur gear 32. This spur gear is mounted between the front

arches 3, 3 and in turn is in mesh with, and driven by, a driving gear 33, which is fixed on the drive shaft 34. This drive shaft is aligned with the motor shaft 10 and is arranged to be clutched therewith, and de-clutched therefrom, through the clutch 35, which is manipulated through the clutch lever 36.

Projecting forwardly from the front flange 23, of the sleeve 21, and fixed to said flange, are the supporting rods 37, preferably four in number, whose forward ends are anchored to the sectional annular anchor 38. A rotatable framework is thus provided which revolves about the pipe 1 and carries the pipe cleaners presently to be described. Pivotaly mounted on the forward end of each rod are the spaced levers 39, 39. Between the forward ends of these levers the cylindrical, rotatable toothed cutters 40 are mounted. Pivotaly mounted on each rod 37, behind the levers 39 is a similar lever 41 whose forward end carries a brush 42. The rear end of each lever 39 and 41 carries a hinged extension 43, having the flat end bearing 44 and interposed between these bearings, and the ends of the levers underneath are the coil pressure springs 45 which operate to hold the cutters 40 and brushes 42 yieldingly against the pipe to be cleaned. The hinged end of each extension 43 has an upstanding arm 46 and adjusting screws 47 are threaded through these arms and work against the corresponding levers underneath. The tension of the springs 45, and the pressure of the pipe cleaning devices, against the pipe may be varied through these adjusting screws 47, and the pipe cleaning devices also thus accommodated to pipes of different sizes.

Operatively connected to the motor 4 there is an air compressor 48 which maintains air pressure in an air pressure tank 49, through the pressure line 50. The numeral 51 designates a paint receptacle, and the numeral 52 designates an annular nozzle around the pipe 1 behind the pipe cleaners. This nozzle has an inside row of perforations, or nozzle openings all the way around the pipe 1, to be painted.

Leading from the compression tank 49, and the paint receptacle 51, respectively are the lines 53 and 54, which unite and enter the nozzle 52. These lines are controlled by the usual valves 55 and 56.

As the machine advances along the pipe the cutters 40 loosen up the incrustations on the pipe, and partially remove the same, and the following brushes 42 sweep off any remaining foreign matter clinging to the pipe. The pipe is thus completely cleaned, and pre-

pared to receive the paint which is sprayed onto the same, in a uniform coat from the nozzle 52.

What I claim is:—

1. A machine for cleaning the outer surface of pipe including a carriage, a motor thereon, a cleaner connected to the carriage, motor operated means for rotating the cleaner about the pipe to clean the same, wheels supporting the carriage on the pipe, some of said wheels having teeth which engage with said pipe.

2. A machine for cleaning the outer surface of pipe including a carriage, a motor thereon, a cleaner connected to the carriage, motor operated means for rotating the cleaner about the pipe to clean the same, wheels supporting the carriage on the pipe, some of said wheels having teeth which engage with said pipe, and means establishing a driving relation between the motor and said toothed carrier wheels.

3. A machine for cleaning the outer surface of pipe including a carriage, a motor thereon, a cleaner connected to the carriage, motor operated means for rotating the cleaner about the pipe to clean the same, wheels supporting the carriage on the pipe, some of said wheels having teeth which engage with said pipe, and other of said wheels having edges which bite the pipe to secure the carriage against rotation on the pipe.

4. A machine for cleaning the outer surface of pipe including a carriage, a motor thereon, a cleaner connected to the carriage, motor operated means for rotating the cleaner about the pipe to clean the same, wheels supporting the carriage on the pipe, some of said wheels having teeth which engage with said pipe, and other of said wheels having edges which bite the pipe to secure the carriage against rotation on the pipe, and means establishing a driving relation between the motor and toothed carrier wheels.

5. A machine for cleaning the exterior surface of pipe lines including a carriage, a motor thereon, a cleaner connected to the carriage, motor operated means for rotating the cleaner about the pipe to clean the same, wheels on which the carriage is mounted, and supporting the machine on the pipe, means for spraying paint on said pipe behind said cleaning means, said spraying means including an annular nozzle around the pipe and means for supplying paint and pressure fluid to said nozzle.

In testimony whereof I have signed my name to this specification.

FRANK KINZBACH.
